[57] ABSTRACT

An apparatus for engaging the lapping surface of a tool with a surface to be lapped by means of driving elements which cause a relative "break-up" motion between said surfaces.

POLISHER-FINER MACHINE

This invention relates generally to an apparatus for the polishing and the fining of ophthalmic lens. In the ophthalmic lens finishing arts, the terms to "polish" and to "fine" are words of art relating to the degree of finish. Since the instant apparatus is used for both polishing and fining the terms will be used interchangeably.

The apparatus of this invention relates to that type of polisher used to finish cylindrical lens. In cylindrical finishers, the lap surface must be held in engagement with the lens surface and moved relative thereto in a path referred to as a "break-up" motion. The break-up motion prevents ridges, grooves and other aberrations in the lens surface which occur when regular or uniform motion is utilized. In break-up motion devices used with cylindrical surfaces, the base and cross-curve of thelapping tool and the lens must be maintained in parallel relationship with one another.

The principal objective of this invention is to provide an apparatus of the above-mentioned type wherein the relative break-up movement between thelapping tool and the lens occurs at high speeds.

Another important objective of this invention is to provide a means for adjustably holding the lap into engagement with the lens surface to be ground while the above-mentioned break-up motion is taking place.

Another important objective of this invention is to provide an improved break-up movement by transmitting a lateral movement to the lens while a combination of movements is given to thelapping tool.

A still further important objective of this invention is in the provision of a linkage apparatus that is rugged, easily disassembled and repaired.

A further objective of the invention is to maximize the relative motion between thelapping tool and the lens to be worked within a small time period and with a minimum of power.

These and other objective of the invention will become more apparent to those skilled in the art by reference to the following detailed description when viewed in light of the accompanying drawings in which:

FIG. 1 is a front elevation of the working components of the apparatus;

FIG. 2 is a side view thereof;

FIG. 3 is a horizontal cross-sectional view along the line 3-3 of FIG. 1;

FIG. 4 is a partial top plan view of the apparatus shown in FIGS. 1, 2 and 3; and

FIG. 5 is a view taken along the line 5-5 of FIG. 1.

Referring now to the drawings wherein like numerals indicate like parts, the numeral 10 indicates the polisher-finer assembly of this invention. The assembly is supported by a framework 12 having a front wall 13, a rearwardly extending lower flange 14, a rearwardly extending upper flange 16 and a rearwardly extending bracket 18 intermediate the flanges 14 and 16. The lower flanges 14 can be supported by a bracing member within a control cabinet or the like not shown.

A pair oflapping units is disclosed each having several elements in common. The unit to the left as viewed in FIG. 1 will be described in detail and corresponding elements of the unit on the right will be indicated by the same numeral with the addition of prime marks.

Adjacent the lower portion of front wall 13, a rearwardly extending bracket 20 is affixed that carries an electric motor 22. The motor 22 has a downwardly extending output shaft 24 to which a pair of pulleys 26

and 28 are mounted. Secured to the front wall 13 by bolts or the like, and disposed laterally outwardly of bracket 20, is a pair of support brackets 30 and 30'. As best seen in FIG. 3, the brackets 30 and 30' rotatably secure cylindrical eccentrics 34 and 34' therein by way of bearing assemblies 36. Each bearing assembly 36 is a combination of raceway and needle bearings for absorbing both radial and longitudinal thrusts. The cylindrical eccentric 34 is formed with an opening 38 radially disposed from the center thereof. The opening 38 rotatably receives a drive rod 40 therethrough which is rotatably supported by bearing 42. A pulley 44 is mounted to the lower end of rod 40 in vertical alignment with the pulley 26. The pulley 44 is mounted for vertical alignment with the pulley 28. The front wall 13 is provided with an opening 48 through which drive belts extend. A belt 50 connects the pulleys 28 and 44 and a belt 52 connects the pulleys 26 and 44. The belts extend through the opening 48.

20 A motor 54 for the eccentric assembly is mounted forwardly of front wall 13 by way of a bracket 56. The motor 54 is disposed approximately midway between the brackets 30 and 30' and has an output shaft 57 extending downwardly therefrom. Affixed to the lower end of shaft 57 is a pair of pulleys 58 and 60. Disposed about the eccentric 34 and connected thereto is a pulley 62. A belt 64 connects the pulleys 58 and 62. A belt 64' connects the pulley 60 and the pulley 62'. At its upper end, the shaft 40 carries an eccentric driver plate 68. Offset from the center of guide plate 68 is a drive pin 70.

As seen thus far, the shaft 40 is rotated by way of the motor 22. It can also be seen that the axis 41 of the drive rod travels in a cylindrical path by virtue of the 35 rotation of the eccentric 34. Shaft 40 is rotated about its own axis and this axis is traveling in a cylindrical path. The pin 70 combines the two movements. The shaft 40 is rotated about its axis 41 at a very much higher speed than the eccentric 34 is rotated. For example, if shaft 40 is rotated at 750 rpm, the eccentric is driven at approximately 10 rpm. In other words, the axis 41 is caused to circumscribe a small circle (about three-sixteenths inch in diameter) at a much lower rate than the shaft 40 rotates.

45 Disposed above the driver plate 68 is a connector rod 72. At its lower end, the connector rod is equipped with a spherical bushing 74 to receive the drive pin 70. At its upper end, the connector rod 72 supports a lap carrier 76 adapted to interchangeably receive lap L having a desired surface configuration 78. A pair of brackets 80 and 82, outwardly extending from wall 13, pivotally supports a gimbal assembly 84 therebetween. The gimbal 84 extends between the brackets 80 and 82. A cross bar 86 is rotatably received by the gimbal and the brackets. A cross bar 88 extends through the rod 72 and the cross bar 86. The gimbal prevents any rotation of rod 72 about its own longitudinal axis. This is important because the cylindrical surface 78 must be maintained in accurate rotational alignment with the surface of the lens to be ground. The gimbal provides a point intermediate the length of the rod 72 to pivotally support same such that the movement given to pin 70 is an accurate and proportional duplication of the movement transmitted from spherical joint 74.

60 It now can be seen that the lap is moved at very high speeds as determined by the rotational speed of shaft 40 and the axis of this orbit moves in a second orbit by

virtue of the eccentric 34. A third relative motion between the lap and lens is determined by a movement by the lens support and retention assembly.

The lens retention assembly is generally indicated by the numeral 100. Disposed above the lap is an arm 102 that carries retention pins 103 and 105. The arm 102 is secured to the outer end of a shaft 104 which is rotatably received in a T-shaped housing 108. Housing 108 is formed with a cross sleeve 109 which is fixedly secured to the shaft 110. The ends of shaft 110 are pivotally and slidably received in the uprights 116 and 118 of a trunnion 112.

As can be seen best in FIG. 2, the other end of shaft 104 is affixed at ball joint 124 to a piston rod 122 of a pneumatic cylinder 120. The cylinder 120 is affixed to bracket 18 at ball joint 126. Compressed air for cylinder 120 is delivered through a conduit 128 and is adjusted by the adjustment and indicator assembly 130. As can be readily understood, the downward pressure that pins 103 and 105 exert against the lens block B can be determined by the air pressure setting.

A third motion is transmitted to the surface between the lens and the lap by way of an electric motor 131. The motor 131 has an output shaft 132 to which a circular plate 136 is affixed at the outer end thereof. A gear reduction unit 138 is disposed between the motor 131 and the output shaft 132. A connecting rod drive pin 139 having a pair of linkage arms 142 and 142' affixed thereto is axially offset from plate 136. The other ends of the linkage arms 142 and 142' are secured to pins 144 and 144' which are connected to housing 108 and 108'. The points of connection to pin 139 are spherical joints which give a universal type connection. As the offset drive pin 139 circumscribes its circle, the sleeve assemblies 108, 108' give a reciprocating motion to shafts 104 and 104' which moves the pins 103-105 (103'-105') laterally back and forth with respect to the lapping tool.

The T-shaped housing 108 is pivoted upwardly to permit a lapping tool to be aligned and secured to the lap carrier 76. The lens to be blocked has the surface to be finished disposed over the tool and the pin carrier assembly 100 is caused to move the pins 103 and 105 into engagement with the block B so as to urge the lens against the lapping tool at a preselected pressure. A break-up motion between the lens and its lapping member is a combination of the rotational motions transmitted by motor 22, the orbital motion transmitted by the motor 54 and the transverse motion given by the motor 132 through pin 138. The linkages combining these motions give a break-up motion that shortens the amount of time necessary to polish and grind a lens as well as substantially eliminating any ridges or other deformations. As those skilled in the art will appreciate, the polishing and fining operation heretofore described takes place in a grinding chamber with the application of a grinding fluid. The control cabinet, the chamber and the conduits for delivering the grinding fluid have not been described so that the principal elements of the drawings could best be disclosed in the drawings.

In a general manner, while there have been disclosed effective and efficient embodiments of the invention, it should be well understood that the invention is not limited to such embodiments as there might be changes made in the arrangement, disposition, and form of the parts without departing from the principles of the pres-

ent invention as comprehended within the scope of the accompanying claims.

I claim:

1. An apparatus for finishing the surface of lens mounted on one side of a lens block having pin-receiving depressions in its other side comprising:
a generally vertically disposed shaft having an upper end and a lower end, said upper end adapted to receive a lapping tool having a polishing surface of a selected base and cross curves,
first means to rotate said shaft about its axis at a first speed,
second means to move said axis in a cylindrical plane at a speed substantially less than said first speed,
drive pin means,
an arm supporting said drive pins over said pin-receiving depressions
third means connected to said arm causing said pins to press the surface to be finished of said lens against said polishing surface,
fourth means to move said arm in a plane substantially parallel to the base curve of said lap tool, whereby a combination of movements between said lens surface and said polishing surface is the sum of the rotation of said shaft about its axis, the movement of said axis in a cylindrical plane and the reciprocating transverse movement of said pins.
2. The invention of claim 1 wherein said first means is an electric motor having a rotating output shaft, and connector means for connecting said output shaft to said first-mentioned shaft.
3. The invention of claim 2 wherein said second means includes an eccentric member having an offset opening rotatably receiving said shaft, second electric motor having a second output shaft and second connector means connecting said second output shaft to said first-mentioned shaft.
4. The invention of claim 2 wherein said first shaft is driven at a relatively greater speed than said eccentric.
5. The invention of claim 1 wherein said third means includes means pivotally mounting said arm, and an air cylinder adjustably urges said pins into said depressions.
6. The invention of claim 1 wherein said fourth means is an electric motor having a lateral output movement.
7. An apparatus for finishing the surface of lens mounted to a lens block comprising
a generally vertically disposed shaft having an upper end and a lower end, said upper end adapted to receive a lapping tool having a polishing surface of a selected base and cross curves,
first means to rotate said shaft about its axis at a first speed,
second means to move said axis in a cylindrical plane at a speed substantially less than said first speed,
third means for engaging said block and for maintaining the lens surface to be ground against said polishing surface,
fourth means to move said third means in a plane substantially parallel to the base curve of said lap tool, whereby a combination of movements between said lens surface and said polishing surface is the sum of the rotation of said shaft about its axis, the movement of said axis in a cylindrical plane and the reciprocating transverse movement of said pins.

8. The invention of claim 7 wherein said first means is an electric motor having a rotating output shaft, and connector means for connecting said output shaft to said first-mentioned shaft.

9. The invention of claim 8 wherein said second means includes an eccentric member having an offset opening rotatably receiving said shaft, second electric motor having a second output shaft and second connector means connecting said second output shaft to said first-mentioned shaft.

10

10. The invention of claim 2 wherein said first shaft is driven at a relatively greater speed than said eccentric.

11. The invention of claim 7 wherein said third means includes an air cylinder adjustably urging said block and lens toward said lapping surface.

12. The invention of claim 1 wherein said fourth means is an electric motor having a lateral output movement.

[57] ABSTRACT

An apparatus for engaging the lapping surface of a tool with a surface to be lapped by means of driving elements which cause a relative "break-up" motion between said surfaces.

REEXAMINATION CERTIFICATE
ISSUED UNDER 35 U.S.C. 307THE PATENT IS HEREBY AMENDED AS
INDICATED BELOW.

Matter enclosed in heavy brackets [ ] appeared in the patent, but has been deleted and is no longer a part of the patent; matter printed in italics indicates additions made to the patent.

AS A RESULT OF REEXAMINATION, IT HAS
BEEN DETERMINED THAT:

Claims 1-4, 6-10 and 12 are determined to be patentable as amended.

Claims 5 and 11, dependent on an amended claim, are determined to be patentable.

1. An apparatus for finishing the surface of lens mounted on one side of a lens block having pin-receiving depressions in its other side comprising:

[a generally vertically disposed shaft having an upper end and a lower end, said upper end adapted to receive a lapping tool having a polishing surface of a selected base and cross curves,]
a frame,

a generally vertically disposed shaft operably having a first portion and a second portion,

said first portion of said shaft having an upper end adapted to receive a lapping tool and having a polishing surface of selected base and cross curves,

gimbal means, portioned intermediate the ends of said first portion of said shaft, for connecting said first portion of said shaft to said frame, to permit oscillation of the upper end of said first portion of said shaft with respect to said frame, and

universal means for connecting a lower end of said first portion of said shaft to an upper end of said second portion of said shaft,

first means to rotate said second portion of said shaft about its axis at a first speed,

second means to move said axis of said second portion of said shaft in a cylindrical plane at a speed substantially less than said first speed,

drive pin means,

an arm supporting said drive pins over said pin-receiving depressions

third means connected to said arm causing said pins to press the surface to be finished of said lens against said polishing surface,

fourth means to move said [arm] drive pins in a plane substantially parallel to the base curve of said lap tool,

whereby a combination of movements between said lens surface and said polishing surface is the sum of the rotation of said second portion of said shaft about its axis, the movement of said axis in a cylindrical plane and the reciprocating transverse movement of said pins.

2. The invention of claim 1 wherein said first means is an electric motor having a rotating output shaft, and connector means for connecting said output shaft to said [first-mentioned] second portion of said shaft.

3. The invention of claim 2 wherein said second means includes an eccentric member having an offset

opening rotatably receiving said second portion of said shaft, second electric motor having a second output shaft and second connector means connecting said second output shaft to said [first-mentioned shaft] eccentric member.

4. The invention of claim 2 wherein said [first] second portion of said shaft is driven at a relatively greater speed than said eccentric.

5. The invention of claim 1 wherein said fourth means is an electric motor having [a lateral] output means connected to said drive pins [movement] for moving drive pins laterally.

6. The invention of claim 1 wherein said fourth means is an electric motor having [a lateral] output means connected to said drive pins [movement] for moving drive pins laterally.

7. An apparatus for finishing the surface of a lens mounted to a lens block comprising: [a generally vertically disposed shaft having an upper end and a lower end, said upper end adapted to receive a lapping tool having a polishing surface of a selected base and cross curves,]

a frame;

a generally vertically disposed shaft operably connected to said frame and having a first portion and a second portion,

said first portion of said shaft having an upper end adapted to receive a lapping tool having a polishing surface of selected base and cross curves,

gimbal means, positioned intermediate the ends of said first portion of said shaft, for connecting said first portion of said shaft to said frame to permit oscillation of the upper end of said first portion of said shaft with respect to said frame, and universal means for connecting a lower end of said first portion of said shaft to an upper end of said second portion of said shaft,

first means to rotate said second portion of said shaft about its axis at a first speed,

second means to move said axis of said second portion of said shaft in a cylindrical plane at a speed substantially less than said first speed,

third means for engaging said block and for maintaining the lens surface to be ground against said polishing surface,

fourth means to move said third means in a plane substantially parallel to the base curve of said lap tool,

whereby a combination of movements between said lens surface and said polishing surface is the sum of the rotation of said second portion of said shaft about its axis, the movement of said axis in a cylindrical plane and the reciprocating transverse movement of said pins.

8. The invention of claim 7 wherein said first means is an electric motor having a rotating output shaft, and connector means for connecting said output shaft to said [first-mentioned] second portion of said shaft.

9. The invention of claim 8 wherein said second means includes an eccentric member having an offset opening rotatably receiving said second portion of said shaft, second electric motor having a second output shaft and second connector means connecting said second output shaft to said [first-mentioned shaft] eccentric member.

10. The invention of claim 2 wherein said second portion of said first shaft is driven at a relatively greater speed than said eccentric.

11. The invention of claim [1] 7 wherein said fourth means is an electric motor having [a lateral] output means operably connected to said third means [movement] for moving said third means laterally.
